(57) **CLAIM**

The ornamental design for bag lock hardware, as shown and described.

DESCRIPTION

FIG. 1 is a perspective view of bag lock hardware, showing my new design;

FIG. 2 is a top plan view thereof;

FIG. 3 is a bottom plan view thereof;

FIG. 4 is a front elevational view thereof, the rear elevational view being identical; and,

FIG. 5 is a right side elevational view thereof, the left side elevational view being identical.

The portions of the bag lock hardware shown in broken lines form no part of the claimed design.
